HARVEY HUBBELL, OF BRIDGEPORT, CONNECTICUT.

MEANS FOR LEVELING AND ALINING FACE-PLATES.

1,275,691.

Specification of Letters Patent. Patented Aug. 13, 1918.

Application filed November 17, 1915. Serial No. 61,923.

To all whom it may concern:

Be it known that I, HARVEY HUBBELL, a citizen of the United States, residing at Bridgeport, county of Fairfield, State of Connecticut, have invented an Improvement in Means for Leveling and Alining Face-Plates, of which the following is a specification.

This invention relates to the class of electric and other fixtures which are adapted to be seated in wall pockets and are provided with finished face plates, and the invention has for its object to provide simple and inexpensive means for leveling the fixtures in the wall pockets and for alining the face plates without tentative adjustments. It is of course well understood that the wall pockets which receive fixtures are roughly and unevenly finished, and that receptacles and other electric fixtures adapted to be seated in pockets are likewise roughly and unevenly finished. The face plates on the other hand are finely finished and are required to be set in perfect alinement in order to give a neat and finished appearance to the work. So far as I am aware, the cut-and-try plan has been the means commonly used for leveling fixtures and for securing alinement of face plates. All the operator usually does is to place the fixture in the wall pocket and secure it in as nearly the proper position as possible by guess-work. The face plate is then attached. If the alinement is not satisfactory, the operator must estimate the necessary change of position of the receptacle, remove the face plate, shift the position of the receptacle, and then attach the face plate again, repeating these operations until the alinement of the face plate is possible, the result being that face plates in high priced work are frequently left more or less out of alinement.

This difficulty and the loss of much time of highly paid workmen is avoided by the use of my present invention, which consists in providing the fixture with an alining plate, that overlies the pocket and is alined with wall, baseboard or casing, as may be required, before the face plate is attached, after which the receptacle is secured in place and the face plate attached to the alining plate, the face plate necessarily assuming the precise alinement of the alining plate.

In the accompanying drawing forming a part of this specification,

Figure 1 is a plan view showing a receptacle and an outlet box in position in a wall pocket, and the alining plate secured to the receptacle, the face plate being removed; 60

Fig. 2 a central longitudinal section corresponding therewith, but showing the face plate in position;

Fig. 3 a view partly in elevation and partly in transverse section, and 65

Fig. 4 is a perspective view on a reduced scale, differing from the other views only in that the face plate is attached by screws instead of by spring fingers.

10 denotes an outlet box adapted to lie in a pocket 11 in a wall 12, and 13 a receptacle or other fixture in the outlet box. My present invention comprises an alining plate 14 which overlies the outlet box and the pocket and to which the face plate 15 is attached. The outlet box is shown as provided with attaching flanges 16 and as attached to the wall by screws 17. The receptacle is shown as provided with attaching flanges 18 and as adjustably secured to the outlet box by screws 19 passing through slots 20 in the flanges. In the present instance, screws 19 are shown as engaging bushings 21 secured in the outlet box. It should be understood, however, that the special details of construction are immaterial so far as the principle of the invention is concerned. Where an outlet box is not used, the receptacle is attached directly to the wall. The alining plate is attached to the receptacle by means of screws 22 which engage attaching flanges 18. The face plate may be attached to the alining plate by means of screws 23, as in Fig. 4, or if preferred, by means of spring fingers 24 secured to the back of the face plate and located and shaped to engage openings 25 in the alining plate. The spring fingers may be formed integral with a finger plate 26, as in my pending application, Ser. No. 11,391, filed Mar. 1, 1915. 95

The operation will be obvious from the drawing and description. The alining plate is secured to the receptacle by screws 22 and then the receptacle is placed in the wall pocket or in the outlet box if used, and is secured in place by screws 19. The fact that the alining plate overlies the pocket insures 105

the leveling of both the receptacle and the face plate. The only adjustment required is to place the alining plate in the desired alinement with baseboard, casing or molding, as may be required, before screws 19 are tightened up. Having placed the alining plate in proper position, it is locked there by tightening up screws 19. The face plate is then secured to the alining plate and is necessarily both leveled and alined thereby.

Having thus described my invention, I claim:—

1. The combination with a box and an electric device therein, of adjusting ears connected with said device, an alining plate adjustably connected with said ears to permit said plate to rest flat against the surface of a wall irrespective of the relative angle of the wall and the box, means for connecting the adjusting ears to said box, and a face plate detachably secured to said alining plate.
2. The combination with a box and an

electric device therein, of adjusting ears connected with said device, an alining plate adjustably connected with said ears to permit said plate to rest flat against the surface of a wall irrespective of the relative angle of the wall and the box, means for connecting the adjusting ears to said box, and a face plate having spring fingers for engaging said alining plate.

3. The combination with a box and an electric device therein, of adjusting ears connected with said device, an alining plate adjustably connected with said ears to permit said plate to rest flat against the surface of a wall irrespective of the relative angle of the wall and the box, said alining plate having inturned tongues, means for connecting said adjusting ears to said box, and a face plate having spring fingers for removably engaging said tongues.

In testimony whereof I affix my signature.

HARVEY HUBBELL
